UNITED STATES PATENT OFFICE

JEAN V. GIESLER, OF KNOXVILLE, TENNESSEE, ASSIGNOR TO THE FULTON SYLPHON COMPANY, OF KNOXVILLE, TENNESSEE, A CORPORATION OF DELAWARE

DESIGN FOR A TOY

Application filed March 19, 1930. Serial No. 34,962. Term of patent 14 years.

To all whom it may concern:

Be it known that I, JEAN V. GIESLER, a citizen of the United States of America, and a resident of Knoxville, Tennessee, have invented a new, original, and ornamental Design for Toys, of which the following is a specification, reference being had to the annexed drawing, forming a part thereof, and which shows a perspective view of a toy embodying my new design.

I claim:

The ornamental design for a toy as shown. In testimony whereof I have signed this specification.

JEAN V. GIESLER.
